THE NORRIS PETERS CO., PHOTO-LITHO., WASHINGTON, D. C.

UNITED STATES PATENT OFFICE.

JAMES A. PAXTON, OF ELLSWORTH, AND JOHN G. PAXTON, OF COLFAX, ILLINOIS.

SHOVELING-BOARD FOR VEHICLES.

SPECIFICATION forming part of Letters Patent No. 712,328, dated October 28, 1902.

Application filed April 14, 1902, Serial No. 102,944. (No model.)

To all whom it may concern:

Be it known that we, JAMES A. PAXTON, residing at Ellsworth, and JOHN G. PAXTON, residing at Colfax, in the county of McLean and State of Illinois, citizens of the United States, have invented certain new and useful Improvements in Shoveling-Boards for Vehicles; and we do hereby declare the following to be a full, clear, and exact description of the invention, such as will enable others skilled in the art to which it appertains to make and use the same.

Our invention relates to improvements in shoveling-boards for vehicles.

15 The object of our invention is to provide a shoveling-board which will be easy to manipulate and effective in operation.

It consists of guides fixed to the side pieces of the said board and means carried at the 20 end of said guides for locking the board in a closed or upright position.

It also consists in certain other novel constructions, as will be hereinafter described and claimed.

25 In the drawings, Figure 1 is a fragmentary perspective view of the back end of a wagon, showing our improved shoveling-board applied thereto. Fig. 2 is an enlarged sectional view through a portion of the same, parts being broken away to more clearly show the form of the guide. Fig. 3 is a detail view of the lock. Fig. 4 is a section through the same. Fig. 5 is a section through the guide and its engaging pin.

35 Like numerals of reference indicate like parts throughout the several views.

Referring to the drawings, the numeral 1 represents the bed of a wagon, 2 the sides, and 3 our improved shoveling-board. The 40 said board may be of any desired size; but we preferably give it such proportions as will fit the back end of the wagon, as shown, the height being equal to the height of the side-boards 2 and the length great enough to extend 45 beyond the said side-boards and reach to the outer face of a strengthening-strip 3^a, which is secured to the end of the said board. Fitted around each end of the said board and 50 to are the side pieces or plates, as 4. We preferably construct these side pieces of sheet metal, although of course any suitable material may be used for this purpose. As each

end of the base-plate 3 is provided with the same construction of side pieces and guides, 55 it is only necessary to describe in detail one of said ends with its working parts. In order that this board might move on the desired arc, with its pivot-joint at the upper edge of the bed 1, as at 3', and to hold the said board against displacement, we provide on the inner face of the side plates the metallic segmental guide 5. This guide is so shaped and positioned that when the said board is lowered to a horizontal position the inner edge 65 6 thereof will be caused to rise a trifle above the upper surface of the bed 1, so as to permit an unobstructed thrust of the shovel over the joint between the two parts—that is to say, the path of the guide is not an arc of a perfect 70 circle, but that end which engages the guide-pin 7 at the time when the board is in a lowered or horizontal position is in operation about one-fourth of an inch nearer the point 6 than the opposite end thereof, the said diversion 75 from the line of the perfect circle being greatest at a point marked 8 and gradually decreasing until it meets the said circle, as at 9. It is obvious that in order for the said guide-pin 7, which is stationary, to continue its travel in 80 the groove 10 of the guide 5 it is necessary for the said end 8 to be raised a distance equal to the diversion of the said guide from the said perfect circle, and in so doing, the guide being riveted or otherwise securely fastened to 85 the side plate 4 of the base-plate 3, the said board will be caused to rise a distance equal to the variation of the aforesaid parts. To clearly show this difference we have shown in Fig. 2 of the drawings a dotted line 11, which 90 is an extension of the true circle struck from pivot-point 3'. Any suitable brace or braces, as 12, may be employed to more securely attach the end 8 to the extended lower corner of the side plates 4.

In order to secure our board against accidental displacement after it has been raised to a horizontal position, we provide at the opposite end of the guide 5 a suitable locking device, as 13. This locking device is circular 100 in form and has a slot, as 14, extending from its outer periphery to the center thereof and in such a position as that when the handle 15 is turned to its highest point the said slot will register with the path of the guide. Thus 105 it will be seen that when the board 3 is turned

to a perpendicular position the pin 7 will slide directly into the slot 14, whereupon it will only be necessary to turn down the handle 15, bringing the solid wall 16 across the path and effectually preventing the falling of the board. In order to give this locking member the proper throw—that is to say, to bring the slot 14 in proper alinement with the path of the guide—we provide upon the outer face of the said member and around the hub of the handle a cut-out portion, as 17, which forms the abutments 18 and 19, the former of which stops the upward movement of the handle 15 when the slot 14 is in register with the path of the guide and the latter arrests the downward movement of the said handle, presenting the solid wall 16, as before mentioned. These shoulders 18 and 19 abut against the lug 19' formed integral with the guides. These locking members and guides are preferably of malleable iron and may be secured in any suitable manner to the side plates 4. An aperture to receive it is formed in the said side plates and the whole mounted within the enlarged portion 20 of the guides.

It will be observed from the drawings that the guide-pin 7 is placed at the strongest point possible—that is, through the side plates and cleats which are placed to receive the ordinary gate 21. This pin is in the form of an ordinary bolt passing through the two members above mentioned and also through a separate plate 23, placed on the outside of the said side plates 2. An antifriction roller or washer 24 is provided between the head of said bolt and the outer face of the plate 23 and forms an enlarged head to travel in the path 10. It will be noted that we employ no hinges whatsoever aside from the guides, the pin sliding in the said guides forming all the pivot necessary.

In order to facilitate the easy removal of our board from engagement with the pin 7, we provide near the end 8 a suitable recess or broken-out portion, as 25, through which the said pin and roller may be slipped. A bridge, as 26, spans the said opening and forms a rigid connection between the parts.

Although we have set forth one particular embodiment of the present improvement, yet we do not desire to limit ourselves to the exact construction herein shown and described, but shall feel at liberty to deviate therefrom to any degree within the spirit and scope of our invention.

Any suitable means might be employed to retain the locking member in position, but we preferably employ the following: The aperture formed in the guide 5 to receive the locking member is formed with a bushing, as 5', to engage the space between the flanges 5^a and 5^b of the said locking member, and a countersink 5^c is formed to receive one of said flanges.

Having now fully described our invention, what we claim as new, and desire to secure by Letters Patent, is—

1. A shoveling-board for vehicles, comprising a base-plate, guides carried thereby, supporting means carried by the vehicle-body and engaging said guides for holding the pivot-point of said base-plate stationary during part of the downward movement thereof and said means being so formed as to gradually raise the same during the rest of the downward movement of the said base-plate, substantially as shown and described.

2. A shoveling-board for vehicles, comprising a base-plate, side plates secured thereto, guides secured to said side plates, supporting means carried by the vehicle-body and engaging said guides for holding the pivot-point of said base-plate stationary during part of the downward movement thereof, and said means being so formed as to gradually raise the pivot-point during the rest of the downward movement of the said base-plate, substantially as shown and described.

3. A shoveling-board for vehicles, comprising a base-plate, side plates secured thereto, guides secured to said side plates, supporting means carried by the vehicle-body and engaging said guides for holding the pivot-point of said base-plate stationary during part of the downward movement thereof, and said means being so formed as to gradually raise the pivot-point during the rest of the downward movement of the said base-plate, substantially as shown and described.

4. A shoveling-board for vehicles, comprising a base-plate, side plates secured thereto, guides secured to said side plates, supporting means carried by the vehicle-body, antifriction-rollers on said supporting means, a groove in said guides to receive the said rollers for supporting the said board, substantially as described.

5. A shoveling-board for vehicles, designed to be hung upon supports on the sides of the vehicle-body, guides carried by said board for engaging said supports and rotatable locking means carried at the extreme end of the said guides, substantially as described.

6. A shoveling-board for vehicles, comprising a base-plate, side plates secured thereto, posterioly-grooved segmental guides secured to said side plates, supporting-rollers carried by the vehicle-body for engaging said grooves, substantially as described.

7. A shoveling-board for vehicles, comprising a base-plate, side plates secured thereto, guides fixed to the inner faces of said side plates and projecting somewhat beyond the sides thereof, and suitable supports to strengthen the said extended portions, substantially as described.

8. A shoveling-board for vehicles, comprising a base-plate, side plates secured thereto, a segmental guide securely fastened to each of the inner faces of said side plates, laterally-projecting pins engaging said guides, the said guides being provided with a cut-out portion as 25 to permit the removal of the guides from engagement with the said pins, substantially as shown and described.

9. A shoveling-board for vehicles, comprising a base-plate, side plates secured thereto, a segmental guide securely fastened to each of the inner faces of said side plates, sup-

- ports projecting from the body of the vehicle and into said guide, said guides being formed for the greater part of their length on the arc of one circle and the remaining part of their 5 length being struck on the arc of a different circle so that one end of the said guides will be somewhat nearer to the pivot-point than the opposite end thereof, substantially as described.
10. A shoveling-board for vehicles, comprising a base-plate, side plates secured thereto, a guide securely fastened to each of the inner faces of said side plates, a pin projecting from each of the sides of the vehicle-body, and engaging said guide, said guide being formed at one of its extreme ends with an enlarged circular bearing portion 20 forming a bearing, a locking member engaging said bearing for locking the board in a closed position, substantially as shown and described.
15. A shoveling-board for vehicles, comprising a base-plate, metallic plates secured to each of the ends thereof, a guide secured to each of the inner faces of the said side plates, antifriction-rollers projecting from the vehicle-body, a groove in each of the guides for receiving the said rollers, a bearing at one end of said guides, a locking member in said bearing, a boss surrounding said bearing and 25 projecting through an aperture formed in the said side plates and a handle formed on the said locking member to facilitate its operation, substantially as described.
20. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
25. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
30. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
35. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
40. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
45. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
50. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
55. A shoveling-board for vehicles, comprising a base-plate, side plates secured thereto, a guide secured to the inner face of each of said side plates, a support projecting from each of the sides of the vehicle-body and into engagement with the said guides, an enlarged portion formed at one end of each of the guides, a boss formed on one side of the said enlarged portion and projecting through an aperture formed in the said side plates, a locking member fixed in said enlarged portion and a projection formed on the said boss for limiting the movement of the said locking member, substantially as described.
60. A shoveling-board for vehicles, comprising a base-plate, side plates secured thereto, a guide secured to each of the inner faces of said side plates, a support engaging each of said guides, a flanged locking member at one end of each of said guides, one of said flanges having abutments formed therein, a projection on the guides for engaging the said abutments and a handle on the said locking member to facilitate its operation, substantially as described.
65. A shoveling-board for vehicles, comprising a base-plate, side plates secured thereto, a guide secured to each of the inner faces of said side plates, a support engaging each of said guides, a flanged locking member at one end of each of said guides, a bushing engaging the space between the flange of the locking member and means for limiting the movement of the locking member, substantially as described.
70. 15. A shoveling-board for vehicles, comprising a base-plate, side plates secured thereto, a guide secured to each of the inner faces of said side plates, a support engaging each of said guides, a flanged locking member at one end of each of said guides, a bushing engaging the space between the flange of the locking member and means for limiting the movement of the locking member, substantially as described.
75. 16. A shoveling-board for vehicles, comprising a base-plate, side plates secured thereto, a guide secured to the inner face of each of said side plates, supports engaging each of said guides, an enlarged portion formed at one end of each of said guides, an aperture formed therein, a bushing formed in said aperture, a flanged locking member embracing the said bushing, one of said flanges engaging a countersunk portion of the guide, abutments formed on the other flange for limiting the movement of said locking member, substantially as described.
80. 17. A shoveling-board for vehicles, comprising a base-plate, side plates secured thereto, a guide carried by each of said side plates, a support engaging each of said guides, a plate secured to each of the sides of the vehicle-body, an aperture formed in said plate, a bolt passed through said aperture and through the side of the vehicle-body and through a cleat on the inner side of the side-boards of the vehicle-body, an antifriction-roller between the said plate and the head of the said bolt at one end and a suitable retaining means at the other, substantially as described.
85. 18. A shoveling-board for vehicles, comprising a base-plate, side plates secured thereto, segmental guides secured thereto, said guides being formed on the arc of one circle for a part of their length and the remaining part being curved so as to raise the pivot end of the said base-plate when the said guide is at one extreme of its movement, substantially as described.
90. 19. A shoveling-board for vehicles, comprising a base-plate, side plates secured thereto, a guide carried by each of said side plates, one end of each of said guides being bent from the arc of a perfect circle, the two arcs formed thereby meeting at a point about midway between the ends thereof, for raising the pivot end of said base-plate during the latter half of its downward movement, antifriction means supporting each of said guides, substantially as shown and described.
95. In testimony whereof we hereunto affix our signatures in presence of two witnesses.
